UNITED STATES PATENT OFFICE.

ARTHUR BREITENSTEIN, OF AKRON, OHIO, ASSIGNOR TO THE MUTUAL MOTOR STORES COMPANY, OF CLEVELAND, OHIO, A CORPORATION.

DESIGN FOR A TIRE-CASING.

51,580.

Specification for Design.

Patented Dec. 18, 1917.

Application filed November 27, 1916. Serial No. 133,788. Term of patent 3½ years.

To all whom it may concern:

Be it known that I, ARTHUR BREITENSTEIN, a citizen of the United States, residing at Akron, in the county of Summit and State of Ohio, have invented a new, original, and ornamental Design for Tire-Casings, of which the following is a specification, reference being had to the accompanying drawing, forming part thereof.

The figure is a fragmentary plan view of a tire casing showing my new design.

I claim:—

The ornamental design for a tire-casing, as shown.

ARTHUR BREITENSTEIN.

Witnesses:

HUGH STEVISON,
HARRY A. BARBER.
